HIGH FREQUENCY FLUID COOLED
THERMIONIC VALVE SYSTEM

Charles Samuel Franklin, London, and Ernest Green, Chelmsford, Essex, England, assignors to Radio Corporation of America, a corporation of Delaware

Application October 27, 1933, Serial No. 695,544
In Great Britain November 9, 1932

9 Claims. (Cl. 250—27)

This invention relates to arrangements wherein a cooling liquid is required to be conveyed to and from a device which is at a point of high frequency potential, such for example, as high frequency liquid cooled thermionic valve arrangements suitable for use in radio and similar high frequency generating systems. An important application of the invention is to high power high frequency thermionic valve arrangements of the kind in which one or more valve electrodes are cooled by means of liquid, generally water, though the invention is applicable to cases where other structures at high frequency potentials are required to be liquid cooled.

The invention will be further understood by referring to the accompanying drawing, in which Fig. 1 is an elevation of a double wound helix of rubber hose; Fig. 2 is also an elevation of a double wound helix of rubber hose, and is similar to Fig. 1, except for the addition of a conducting shield; Fig. 3 is an elevation of a double wound helix of rubber hose which is surrounded by a plurality of conducting rings and insulating spacing members which are alternately assembled around the double helix of rubber hose. A portion of the rings and spacing members is shown in section.

As is well known it is practically necessary in high power high frequency radio and like transmitters to cool a valve electrode or electrodes by means of a liquid, generally water, and this is customarily accomplished by employing thermionic valve structures wherein the anode forms part of the envelope and is cooled by passing cooling liquid, generally water, around the outside thereof, the said cooling liquid being led to and from the valve or valves through suitable pipes e. g. rubber hose. As is well known the efficiency of such a liquid cooled high frequency arrangement is liable to be seriously lowered by reason of high frequency losses occurring in the cooling medium or in the hose or the supporting structure carrying the same. For example, consider the usual case illustrated in the accompanying Figure 1, in which the anode of a thermionic valve (not shown) (or other apparatus at high frequency potential) is cooled by water led to and from it by means of a double wound helix of rubber hose 1, the said hose being supported by a central structure 2 about which the turns of the hose lie; in such an arrangement one end (the end A) of the coiled hose structure will be subjected to a steady direct current potential, and also to high frequency alternating potential, the

other end (the end B) being substantially at earth potential, and, owing to self-capacity effects, the high frequency potential will fall rapidly in the first few turns of the hose so that for these turns there will be steep high frequency voltage gradients with consequent large dielectric losses in the cooling fluid, the hose and the supporting structure. Various expedients have been devised to meet this well known difficulty and the present invention has for its object to provide an improved simple and satisfactory arrangement for meeting the said difficulty.

According to the main feature of this invention the upper end A of the cooling liquid piping system which is subjected to high frequency alternating current potentials is enclosed in or surrounded by a conducting shield (i. e. with what may be termed a "corona" ring) which is electrically connected to the source of said potential. In this way the high frequency potential gradients are reduced and therefore also the dielectric losses in the cooling liquid, hose and supporting structure.

In one form of construction in accordance with the invention and illustrated in the accompanying Figure 2, the conducting shield is actually in the form of a corona ring structure 3 which is well known per se in high voltage electrical power transmission systems, and the support 2 about which the rubber hose or other piping is coiled is also utilized to carry the corona ring structure. Connection from the source of high frequency potentials to the ring structure 3 is made via the lead 4.

The invention also envisages meeting the aforementioned difficulty by means of a special and simple constructional arrangement in accordance with the general principles set forth in U. S. patent application, Serial No. 586,369, filed Jan. 13, 1932, wherein is described an arrangement in which a capacity potentiometer is employed in effective parallel with the liquid carrying piping, tappings upon the potentiometer being utilized to determine and thus to reduce the high frequency voltage gradient down the piping. The particular construction embodying this principle and proposed by the present invention is illustrated (partly in section) in the accompanying Figure 3 from which it will be seen that the coil of liquid carrying piping 1 is surrounded by a series of washer shaped conducting rings, said rings 5 closely surrounding the coil and being insulated therefrom, said rings being side by side along the length of the coil. Consecutive rings are insulated from each other by means of spacing or

interposed rings 6 of mica, or other di-electric. The ring which surrounds the high frequency high potential end (A) of the coil of piping is connected via a lead 7 to the source of high frequency apparatus supplying the high frequency potential, i. e. to the same point to which the piping supplies fluid to the anode of a thermionic valve while the ring surrounding the other end of the coil is connected to earth via a lead 8. The high frequency voltage gradient down the piping is determined and reduced by capacity coupling from the potentiometer.

Having now particularly described and ascertained the nature of our said invention and in what manner the same is to be performed, we declare that what we claim is:

1. An arrangement wherein apparatus at high frequency alternating current potential is cooled by a cooling liquid comprising a piping system, characterized in that that end of the cooling liquid piping system which is subjected to high frequency alternating current potentials is surrounded by a conducting shield which is electrically connected to the source of high frequency alternating current potentials.

2. A high frequency liquid cooled thermionic valve arrangement suitable for use in radio high frequency generating systems, and wherein valve electrodes of apparatus operated at high frequency alternating current potential are cooled by a cooling liquid comprising a piping system, characterized in that that end of the cooling liquid piping system which is subjected to high frequency alternating current potentials is surrounded by a conducting shield which is electrically connected to the source of high frequency alternating current potentials.

3. In combination a thermionic valve having a liquid cooled anode, a piping system in the form of a double wound helix the pipes at one end of which feed cooling liquid to and from said anode and the pipes at the other end of which communicate with a source of liquid supply at substantially earth potential, comprising a piping system characterized in that the end of the double wound helix adjacent (as regards the liquid flow) the anode is surrounded by a corona ring structure which is electrically connected to said anode.

4. An arrangement wherein apparatus at high frequency alternating current potential is cooled by cooling liquid comprising a piping system, characterized in that the said piping system is surrounded by a series of washer-shaped conductive rings closely surrounding the coil, insulated therefrom, and arranged side by side along the length thereof, said conductive rings being assembled alternating with interposed rings of di-electric material, the end conductive ring surrounding the high frequency potential end of the piping system being connected to the source of high frequency potential and the other end conductive ring being connected to earth.

5. A high frequency liquid cooled thermionic valve arrangement for use in radio high frequency generating systems and wherein valve electrodes of apparatus operated at high alternating current potential is cooled by cooling liquid comprising a piping system, characterized in that

the said piping system is surrounded by a series of washer-shaped conductive rings closely surrounding the coil insulated therefrom and arranged side by side along the length thereof, said conductive rings alternating with interposed rings of di-electric material, the end conductive ring surrounding the high frequency potential end of the piping system being connected to the source of high frequency potential and the other end conductive ring being connected to earth. 10

6. In combination a thermionic valve having a liquid cooled anode, a piping system in the form of a double wound helix the pipes at one end of which feed cooling liquid to and from said anode and the pipes at the other end of which communicate with a source of liquid supply at or substantially at earth potential, characterized in that the coil of liquid carrying piping is surrounded by a series of washer-shaped conductive rings closely surrounding the coil, insulated therefrom, and arranged side by side along the length thereof, said conductive rings alternating with interposed rings of di-electric material, the end conductive ring surrounding the high frequency high potential end of the coil of piping being connected to the source of high frequency potential and the other end conductive ring being connected to earth, substantially as described. 15

7. A high-frequency liquid cooled thermionic valve arrangement for use in a high-frequency generating system, wherein at least one of said valves is cooled by a liquid comprising a piping system assembled in a helical coil-like arrangement, one end of said piping system connected to a source of high-frequency potential, the other end of said piping system being connected to earth, and a corona ring located at the top of said helical coil-like arrangement. 20

8. A high-frequency liquid cooled thermionic valve arrangement for use in a high-frequency generating system, wherein at least one of said valves is cooled by a liquid comprising a piping system assembled in a helical coil-like arrangement, one end of said piping system connected to a source of high frequency potential, the other end of said piping system being connected to earth, a plurality of metallic rings and insulating spacing members alternately assembled to reduce dielectric losses in the cooling liquid flowing in said helical coil-like arrangement. 25

9. A high-frequency liquid cooled thermionic valve arrangement for use in a high-frequency generating system, wherein at least one of said valves is cooled by a liquid comprising a piping system assembled in a helical coil-like arrangement, one end of said piping system connected to a source of high-frequency potential, the other end of said piping system being connected to earth, a plurality of metallic rings and insulating spacing members alternately assembled to reduce dielectric losses in the cooling liquid flowing in said helical coil-like arrangement, the diameter of said metallic rings and said spaced members gradually decreasing toward the top of said helical coil-like arrangement. 30
